US0D1113933S

(12) **United States Design Patent** (10) **Patent No.:** **US D1,113,933 S**
(45) **Date of Patent:** **** Feb. 17, 2026**

(54) **HANDLE FOR PORTABLE ELECTRONIC DEVICE**

(71) Applicant: **Getac Technology Corporation**, New Taipei (TW)

(72) Inventor: **Wei-Sen Lu**, Taipei (TW)

(73) Assignee: **Getac Technology Corporation**, New Taipei (TW)

(**) Term: **15 Years**

(21) Appl. No.: **29/901,075**

(22) Filed: **Aug. 29, 2023**

(51) LOC (15) Cl. **14-03**

(52) U.S. Cl.

USPC **D14/440**

(58) **Field of Classification Search**

USPC ..... D14/440, 315, 318, 324, 328, 341, 344, D14/345, 389, 392, 444, 445; D19/26, D19/62; D3/247, 290, 299, 20 CPC A45C 2011/002; A45C 2011/003; A45C 2200/15; A45F 2200/05; A45F 2200/16; A45F 2200/525; G06F 1/1628; G06F 1/1632; G06F 1/1669; G06F 2200/1633; H04B 1/3888; H04M 1/185

(57) **CLAIM**

The ornamental design for a handle for portable electronic device as shown and described.

DESCRIPTION

FIG. 1 is a front, top and right side perspective view of a handle for portable electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom and left side perspective view of the handle for portable electronic device.

The dashed broken lines in the drawing depict portions of the handle for portable electronic device that form no part of the claimed design.

The dot-dot-dash broken lines in the figures represent an unclaimed boundary line and form no part of the claimed design.

1 Claim, 6 Drawing Sheets
